*Primary Examiner—Prabhakar G. Deshmukh**Attorney, Agent, or Firm—Cislo & Thomas***[57] CLAIM**

The ornamental design for a bowling ball pushing apparatus, as shown and described.

DESCRIPTION

FIG. 1 is a perspective view of a bowling ball pushing apparatus, showing my new design;

FIG. 2 is a right side elevational view of the apparatus, with the left side elevational view being a mirror image thereof;

FIG. 3 is a top plan view; and,

FIG. 4 is a bottom plan view.
